UNITED STATES PATENT OFFICE.

ARTHUR S. ALEXANDER AND ALFRED VISCHER, OF NEW YORK, N. Y.

ATTACHMENT FOR MOUTH-HARMONICAS.

SPECIFICATION forming part of Letters Patent No. 703,752, dated July 1, 1902.

Application filed January 18, 1902. Serial No. 90,305. (No model.)

To all whom it may concern:

Be it known that we, ARTHUR S. ALEXANDER and ALFRED VISCHER, citizens of the United States, and residents of the city of New York, borough of Manhattan, in the county and State of New York, have invented a new and Improved Attachment for Mouth-Harmonicas, of which the following is a full, clear, and exact description.

10 The object of the invention is to provide a new and improved attachment for mouth-harmonicas which is simple and durable in construction, arranged for convenient and quick attachment to or detachment from a 15 mouth-harmonica, and more especially designed to greatly reinforce the strength of the tone and to give it a brass-instrument quality.

The invention consists of novel features 20 and parts and combinations of the same, which will be more fully described hereinafter and then pointed out in the claims.

A practical embodiment of the invention is represented in the accompanying drawings, 25 forming a part of this specification, in which similar characters of reference indicate corresponding parts in all the views.

Figure 1 is a front elevation of the improvement in position on the mouth-harmonica. 30 Fig. 2 is a rear sectional elevation of the same on the line 2 2 of Fig. 3. Fig. 3 is an inverted sectional plan view of the same on the line 3 3 of Fig. 1, and Fig. 4 is a transverse section of the same on the line 4 4 of Fig. 3.

35 The attachment consists, essentially, of a bell or horn A, closed at one end and having in its side an elongated opening B for receiving the mouth-harmonica C, provided on the rear portions of its cover with longitudinally-extending ribs D, adapted to abut against the inside of the bell or horn A when inserting the mouth-harmonica C from the inside of the horn into the opening B. Thus the ribs D limit the outward movement of the 40

45 mouth-harmonica C when in position on the horn or bell, and in order to firmly lock the mouth-harmonica in position we engage one end thereof with a fixed bracket E and the other end is engaged by a bolt F, mounted 50 to slide in a suitable guideway G, arranged on the inside of the bell or horn, as plainly indicated in Fig. 3.

The bracket E is located at or near the closed end of the bell or horn A, and the bolt F and its bearing G are arranged near the 55 outer open end of the said bell or horn, and the bolt is provided with a handle F', adapted to be taken hold of by the operator to push the bolt into a closed position, as shown in Fig. 3, or to allow of withdrawing the bolt 60 from the mouth-harmonica when it is desired to remove the harmonica from the bell or horn A.

It is understood that by the arrangement described the tone - discharge end of the 65 mouth-harmonica C extends a distance within the bell or horn A, as plainly indicated in Figs. 3 and 4, and at the same time the mouth-harmonica fits snugly onto the walls of the opening B, so that the sounds which emanate 70 from the mouth-harmonica when the latter is played pass directly into the bell or horn and finally through the open end thereof to the outside in a greatly reinforced state and of a quality corresponding to that of a brass 75 instrument.

As the mouth-harmonica can be readily detached from the bell or horn A, it is evident that the said harmonica can be played without the bell or horn attachment, it being understood 80 that the mouth-harmonica in its general construction is that of an ordinary mouth - harmonica, and the ribs D, which serve as a stop when in the bell, also serve to strengthen the cover, so as to prevent pressing in thereof when the mouth-harmonica is used without the bell or horn.

The sides of the cover of the mouth-harmonica are tapering, as plainly shown in Fig. 4, so that the harmonica can be readily inserted into the opening B from the inside of the bell. By having the cover tapering, as described, the entrance end is reduced in thickness to a minimum, so that the player is not required to open his mouth unduly 95 wide.

Having thus described our invention, we claim as new and desire to secure by Letters Patent—

1. A mouth-harmonica attachment, comprising a bell having in its side an opening extending lengthwise of the side, and terminating a distance from each end of the bell, the opening being arranged to receive the 100

mouth-harmonica from within the bell, and fastening devices within the bell for holding the mouth-harmonica in position, as set forth.

2. The combination with a mouth-harmonica, of an attachment comprising a bell having in its side an opening into which the said mouth-harmonica is inserted from within the bell, and fastening devices in the bell for holding the mouth-harmonica in position thereon, the discharge edge of the harmonica extending a distance within the bell, as set forth.

3. A mouth-harmonica attachment, comprising a bell having in its side an opening for the reception of the mouth-harmonica, and fastening devices in the bell for holding the mouth-harmonica in position, one of the said fastening devices being fixed at the closed end of the bell and the other fastening device being movable at the mouth of the bell, as set forth.

4. The combination with a mouth-harmonica having longitudinal ribs on its cover, of a bell having in its side an opening for the insertion of the mouth-harmonica, the said

ribs abutting against the wall of the bell at the inside thereof, and fastening devices for holding the mouth-harmonica in position on the bell, as set forth.

5. The combination with a mouth-harmonica having tapering sides, of a bell provided in its side with an opening having a width somewhat less than the width of the mouth-harmonica at the discharge edge thereof for the side walls of the opening to limit the outward movement of the mouth-harmonica on inserting the latter into the said opening from the inside of the bell, the said discharge edge extending a distance within the bell, and fastening devices for holding the mouth-harmonica in position on the bell, as set forth.

In testimony whereof we have signed our names to this specification in the presence of two subscribing witnesses.

ARTHUR S. ALEXANDER.
ALFRED VISCHER.
